US00D790699S

(12) **United States Design Patent** (10) **Patent No.:** **US D790,699 S**
(45) **Date of Patent:** ** *Jun. 27, 2017

(54) **SURGICAL TOOL**

(71) Applicant: **Medtronic PS Medical, Inc.**,
Louisville, CO (US)

(72) Inventors: **Shane S. Dexter**, Keller, TX (US);
Zachary Heiliger, Flower Mound, TX
(US)

(73) Assignee: **Medtronic PS Medical, Inc.**,
Louisville, CO (US)

(*) Notice: This patent is subject to a terminal disclaimer.

(**) Term: **14 Years**

(21) Appl. No.: **29/521,690**

(22) Filed: **Mar. 25, 2015**

(51) LOC (10) Cl. **24-02**

(52) U.S. Cl.

USPC **D24/146**

(57) **CLAIM**

The ornamental design for a surgical tool, as shown and described herein.

DESCRIPTION

FIG. 1 is a top and rear perspective view of a surgical tool in accordance with principles of the present disclosure; FIG. 2 is a bottom and rear perspective view thereof; FIG. 3 is a rear end view thereof; FIG. 4 is a front end view thereof; FIG. 5 is a left side view thereof, the right side view being a mirror image; FIG. 6 is a top plan view thereof; and, FIG. 7 is a bottom plan view thereof. The broken lines shown in FIGS. 1-7 illustrate portions of the surgical tool that form no part of the claimed design.

1 Claim, 6 Drawing Sheets
